UNITED STATES PATENT OFFICE

OTTO BÖHM, OF BERLIN, GERMANY, ASSIGNOR TO TELEFUNKEN GESELLSCHAFT FÜR DRAHTLOSE TELEGRAPHIE, M. B. H., OF BERLIN, GERMANY, A CORPORATION OF GERMANY

RECEIVING SYSTEM

Application filed January 30, 1929, Serial No. 336,112, and in Germany March 31, 1928.

This invention relates to the reception of short wave signals, and more particularly to a method and means for the utilization of echo signals to aid in the reception of short wave signals.

In the reception of short waves antenna systems comprising reflectors may be employed, for the purpose of receiving radiations from a definite direction, and to screen off radiations from the opposite direction. Now, it has been found that in spite of the screening effect of a reflector, the antennæ are excited more or less strongly also by waves coming from the opposite direction, and one particular kind of trouble in operation is due to the fact that not only the signal coming in from the regular direction of reception, but also the same signal after having passed around the earth in the opposite sense reaches the receiving point, and excites the receiving antenna. Indeed, it happens quite often that this retrogressive signal comes in with far greater strength than the direct signal, so that, even in a case where only a fraction of the retrogressive signal happens to excite the antenna, owing to the effect of the reflector, the ensuing intensity may nevertheless be substantially stronger than the volume of the directly received signal. Now, the object of the present invention is to utilize for reception both the directly received as well as the retrogressive signal, and to incidentally diminish such disturbances as are occasioned by the time-difference between the direct and the retrogressive signal.

According to the invention, two antennæ or antenna systems are employed at the receiving station, each thereof being equipped with a reflector. But the reflector of one antenna system is mounted at the side opposite the place of mounting of the reflector of the other antenna system, while the receiver antennæ of both antenna systems are connected with a joint receiving apparatus.

My invention is described more in detail in the following specification, accompanied by a drawing in which one form of my invention is schematically illustrated.

For a better understanding of the scheme, reference is made to the drawing. Let *a* be

the wave arriving from one direction and *b* the wave carrying the same signal from the other direction. A1 is one antenna or antenna system and is provided with a reflector R1, while A2 is the other antenna system and is provided with a reflector R2, the reflectors serving to make the antennæ unidirectional in opposite directions. The two antennæ are coupled by wires or intermediate circuits K1 and K2, respectively, with a common receiver E. If there is no time-difference between signals *a* and *b*, as if the receiver and transmitter are at opposite points on the earth's surface, the receiver E will be acted upon simultaneously by the two antenna systems.

However, as a general rule the distance between the transmitter and the receiver will be such that the distance in one direction is shorter than that in the other. Supposing that signal *a* comes in over the shorter route, then the same signal *b* will come in over the other route with some time lag. In order that then, the indicator may be influenced simultaneously by both signals, it is necessary to insert in the connecting wire between antenna A1 and the receiver E a means whereby the transmission of the signal is retarded, and this by an amount of time just equalling the time of delay in arrival at the receiving end of the signal *b*, compared with the arrival of signal *a*. Referring to Figure 1, the said retarding means is diagrammatically shown and indicated by the rectangle V. The same may consist, for instance, of a time-lag or retarding relay or the like.

In order to explain the diminution of the disturbance by means of such an arrangement, we will assume that the reflector allows the passage of only one-tenth the intensity of the retrogressive signal. Antenna A1 then picks up intensity *a* and one-tenth of the disturbing intensity *b*. Hence, in this customary scheme the stray or disturbing intensity or signal ($\frac{1}{10}b$) may turn out substantially larger than intensity *a* of the direct signal. The second arrangement receives intensity *b* and the stray intensity $\frac{1}{10}a$. Also in this system taken by itself the intensity of the retrogressive or stray signal may under certain circumstances, turn out far stronger than

the direct signal. Now, if according to this invention both arrangements are combined in such a way that the time interval or difference between signals a and b is neutralized, the receiver will be acted upon by a signal strength $a+b$. The disturbing signals will then be $\frac{1}{10}a$ and $\frac{1}{10}b$, respectively, and they can never exceed the value $\frac{1}{10}(a+b)$. Hence, the disturbing intensity in this instance is always independent of the value of a and b , indeed, it will amount to only a fraction of the sum total of the two signal strengths.

I claim:

- 15 1. A receiving system, especially for short waves comprising two antennæ or antenna systems, each of which is furnished with a reflector, the reflector of one of said systems being mounted upon a side opposite the reflector of the other system, said two antennæ or antenna systems being associated with a joint receiver responsive to all of the signal energy collected upon the two antennæ or antenna systems.
- 20 2. A receiving system, especially for short waves, comprising two antennæ or antenna systems, each of which is furnished with a reflector, the reflector of one of said systems being mounted upon a side opposite the reflector of the other system, said two antennæ or antenna systems being associated by means of leads with a joint receiver responsive to all of the signal energy collected upon the two antennæ or antenna systems, one of said
